UNITED STATES PATENT OFFICE.

WILLIAM H. HILL, OF CANTON, OHIO.

FUEL VAPORIZER.

Application filed January 8, 1921. Serial No. 435,779.

To all whom it may concern:

Be it known that I, WILLIAM H. HILL, a citizen of the United States, residing at 415 Wells St., S. W., Canton, Ohio, have invented certain new and useful Improvements in Fuel Vaporizers, of which the following is a clear, full, and exact description.

This invention relates to apparatus for the treatment of liquid fuels to prepare them for use in combustion devices and particularly to apparatus for effecting the rapid, progressive and complete volatilization or vaporization of the more heavy or less volatile liquid fuels, such as kerosene, to render them available for convenient, efficient and economical use in combustion devices and especially in internal combustion motors. The invention is herein shown as embodied in an auxiliary device adapted to be used in connection with the usual carburetor of an internal combustion motor, but it will be understood that the invention is not restricted to the illustrated embodiment and uses, and that many features of the invention are of general utility in the art to which the invention relates.

A general object of the invention is to facilitate the formation of the desired explosive mixture when dealing with certain classes of fuels in vaporizing apparatus of the general type of that disclosed in my prior applications Ser. No. 211,333 filed Jan. 11, 1918, Serial No. 233,233 filed May 8, 1918, Ser. No. 243,172 filed July 3, 1918 and Ser. No. 251,765, filed Aug. 28, 1918.

An important feature of the present invention is the provision of novel means for insuring the discharge of the vaporized fuel from the apparatus as it is formed in response to the demand from the internal combustion motor or other device with which it is to be used, this means operating in such manner that both the composition of the mixture and its temperature will be such as to insure uniformity of combustion.

Other objects and important features of the invention will appear from the following description and claims, when considered in connection with the accompanying drawings, in which—

Fig. 1 is a side elevation of a vaporizing apparatus embodying the present invention.

Fig. 2 is a vertical section through the apparatus shown in Fig. 1.

Fig. 3 is a section on the line 3—3 of Fig. 2, and

Fig. 4 is a section on the line 4—4 of Fig. 3.

In the utilization of the heavier hydrocarbon fuels, such as kerosene, some volatilization or vaporization of the fuel can usually be obtained at ordinary atmospheric temperatures by the use of the ordinary carburetor without the application of more heat than is provided by the usual air heating means provided with such carburetors. In order to obtain a complete volatilization of kerosene or others of the heavy hydrocarbon fuels under the varying conditions of atmospheric temperature, particularly in cold weather, it has usually been found necessary to provide further means for heating the fuel than has been provided with the ordinary carburetor intended for use with the more volatile fuels. Many devices have been provided for effecting such heating, some of which have operated with a fair degree of success, but for the most part these devices have been so constructed that in attempting to apply the degree of heat requisite to the complete vaporization of the kerosene or other heavy hydrocarbon fuel, they have applied to the more volatile constituents of the fuel heat of an intensity much greater than that required to vaporize them, with the result that some of these constituents have been cracked and changed into less combustible compounds, with the usual resultant knocking and rapid carbonization of the internal combustion motors with which the devices have been used.

As hereinabove suggested, the present invention aims to provide a device for use in effecting the complete vaporization or volatilization of a liquid fuel which will so apply the vaporizing heat as to avoid applying an excessive amount of heat to the more volatile constituents of the fuel and which, nevertheless, will operate rapidly and efficiently throughout the range of demands made upon it by the ordinary internal combustion motors and will supply said motors, under the varying conditions of atmospheric temperature and in response to the varying demands of such motors, with the proper mixtures of air and completely volatilized and uncracked fuel. In other words, the invention aims to provide a device for use in effecting the rapid, progressive and complete volatilization of a liquid fuel or, as herein particularly illustrated and described, for completing the volatilization of a liquid fuel

that has been begun in another device, which will operate with the highest efficiency under substantially all conditions to which it will be subjected and in response to the varying demands which will be made upon it by the ordinary internal combustion motor, particularly those used upon motor vehicles.

The illustrated embodiment of the invention, which is particularly intended for use with an ordinary carburetor and which is adapted to be located between the carburetor and the intake of an internal combustion motor, comprises means for separating from the air and fuel mixture coming to the apparatus from the carburetor the unvolatilized portions of the fuel and means for vaporizing or volatilizing the unvolatilized portions thus separated from the mixture. In the illustrated construction, the separating chamber 2 is formed in the upper part of a cylindrical casing 4 and the vaporizing chamber 6 is located in said casing below the separating chamber.

The casing 4 which may be formed as a casting of suitable metal such, for example, as aluminum or bronze, has preferably formed integral with it a tangential inlet 8 provided with a flange 10 having bolt holes 12 by which the inlet may be connected to a pipe or other suitable conduit leading from the carburetor with which the device is to be used. The casing 4 is also provided with a partition 14 separating the chamber 2 from the chamber 6, this partition extending about three-quarters of the way around the inner wall of the casing 4 leaving an opening 16 between the chamber 2 and the chamber 6 through which both the air and the volatilized portions of the liquid fuel must pass before being discharged from the apparatus and through which the unvolatilized portions of the liquid fuel, which by the centrifugal movement of the fuel through the separating chamber are thrown against the inner wall of the chamber, pass down into the vaporizing chamber and around and about the inner wall of said chamber, the centrifugal movement continuing into the lower chamber 6.

The separating chamber 2 is annular in shape, having an inner wall concentric with its outer wall, the inner wall being formed by the discharge pipe 18 which extends down through a concentric opening provided in the partition 14 and which fits tightly in said opening so that with the wall of the casing 4 it bounds an annular passage between the inlet 8 and the opening 16 in the chamber 2, the pipe 18 also fitting tightly against a curved surface 20 provided on the inlet 8 thus separating the opening 16 from the inlet. The discharge pipe 18 has preferably formed integral with it a shouldered flange 22 adapted to rest upon and fit within an in-turned flange 24 on the upper end of the cas-

ing 4 and to which flange it may be connected by suitable bolts or screws 26. At its upper end the discharge pipe 18 is also provided with a flange 28 adapted to be connected by bolts or screws 30 to a flange 32 on a pipe 34 leading to the intake manifold of the internal combustion motor with which the device is to be used.

As above pointed out, the discharge pipe 18 extends down through the chamber 2, 75 constituting the inner wall of an annular passage in said chamber, and opens into the chamber 6, the opening in the chamber 6 being preferably just below the partition 14 between the chambers 2 and 6. Preferably 80 integral with the pipe 18 are depending ears 36 which carry a block 38 connected to said ears by screws 40, the block 38 having a threaded opening concentric with the passage in the discharge pipe 18 into which is 85 screwed a second discharge pipe 42 tapered at its upper end at 44. The purpose of the second discharge pipe 42 is to insure discharge of the heavier and less volatile portions of the fuel as they are volatilized or 90 vaporized in the lower and hotter portions of the chamber 6. To this end, means are provided for setting up a pressure differential in the discharge pipe 42, the illustrated means working on the venturi principle and comprising a restricted passage 46 in the discharge pipe 18 about the tapered upper end 44 of the pipe 42. In the illustrated construction, the restricted passage 46 is formed 95 in a block 48 adapted to fit within the pipe 100 18 and to be held in position in said pipe by any suitable means such as the screw 50. By reason of its threaded connection with the block 38, the pipe 42 may be adjusted up and down in the restricted passage 46 to secure 105 the proper suction effect and it may be secured in adjusted position by a lock nut 52.

The illustrated vaporizing means like those disclosed in my prior applications Serial #233,233, filed May 8, 1918, for Letters 110 Patent for improvements in liquid fuel vaporizing devices, and Serial No. 251,765, filed August 28, 1918, for Letters Patent for improvements in kerosene vaporizers, of which applications this application is in 115 part a continuation, operates by the action of a differentially heated vaporizing surface on liquid fuel which is caused to pass over said surface from the region of the lowest heat through the intermediate gradations 120 to the region of highest heat. To obtain such heating of the vaporizing surface in the illustrated construction the casing 4 is made of the shape shown in Fig. 2 of the drawings, the chamber 6 having a tapered 125 or conical intermediate wall portion 54 between the upper part of the chamber 6 and a lower cylindrical part 56 of an internal diameter considerably less than that of the upper part. Upon the outer wall of the 130

part 56 of the chamber 6 in the casing 4 the casing is provided with heat-collecting flanges 58 extending about said casing and this part of the casing 4, and also a part of 5 the tapered intermediate portion of the casing, is adapted to be located within a chamber provided in a second casing 60 of the shape shown in plan in Fig. 3, the casing 60 having an opening 62 at one end and an 10 opening 64 at its other end whereby it may be inserted in the exhaust pipe of an internal combustion motor to permit the exhaust gases to pass through the chamber in 15 said casing and over the heat-collecting flanges 58 and about the outer wall of the chamber 56 in the casing 4, thus heating the lower end of the vaporizing chamber 6, that is, the part 56 of said chamber, to a relatively high degree of heat as compared with 20 the heating of the upper part of said chamber.

It will be seen that no provision is made for heating the wall surface 66 in the upper part of the chamber 6 over which the 25 fuel to be vaporized passes, except by conduction along the wall from the directly heated lower wall of the chamber 6. This heating by conduction along the wall furnishes a degree of heat in the vaporizing 30 surface 66 in the upper part of the chamber sufficient to vaporize the more volatile parts of the unvaporized fuel which passes over said wall. It will be obvious that the 35 intensity of the heat increases toward the lower end of the wall 66, the conical part 54 of the wall of the chamber being still hotter because a part of it is directly exposed to the exhaust gases upon its outer side, and that the heat in the wall of the part 40 56 of the chamber 6 will be much more intense than that in the wall 66. Moreover, the radiant heat in the part 56 of the chamber 6 will have a much more marked effect upon the fuel because of the lesser diameter 45 of this chamber.

For convenience in assembling, the casing 4 is provided with a flange 67 bevelled on its outer edge to fit the bevelled or counter-sunk edge 68 of an opening in the upper side of 50 the casing 60, through which the part of the casing 4 having the heat collecting flanges 58 thereon may be inserted into the casing 60. The casing 60 is also provided in its lower side with an opening 70 into 55 which the lower end of the reduced part of the casing 4 extends, this lower end of the casing 4 being tapped to receive the threaded stem 72 of a clamping member 74. The clamping member 74 has a central drainage 60 passage 76, and a pet cock 78 tapped into the end of the member 74 controls this passage.

From the foregoing description the operation of the device will readily be understood. The intake 8 being connected to an

ordinary carburetor such as is used with an internal combustion motor and the discharge pipe 18 being connected to the intake manifold of the motor, the suction stroke of the motor piston will cause a mixture of air and atomized and partially volatilized hydrocarbon fuel to be drawn into the intake 8 and about the annular passage in the centrifugal or separating chamber 2. The intake 8 being tangential to the curved 75 inner wall of the chamber 2, the movement of the mixture along the annular passage will cause the heavier unvolatilized portions of the fuel to travel about the outer part of the passage and to be thrown against the 80 outer wall of the chamber 2. Since the discharge pipe 18 opens into the chamber 6, the draft from the motor upon the apparatus forces the now centrifugally moving air, vapor and unvolatilized fuel particles 85 through the opening 16 into the lower chamber 6 where the heavier unvolatilized portions of the fuel travel down over the wall 66 of the chamber. Some of the air and volatilized portions of the fuel being displaced 90 toward the center of the chamber are at once drawn into the discharge pipe 18 and up through the restricted passage 46 in the discharge pipe. By the well known venturi principle of operation the air and vapor passing through the restricted passage 46 become rarified, thus creating a pressure differential between the two ends of the auxiliary discharge pipe 42 which tends to move the vaporized portions of the 95 fuel in the lower part 56 of the chamber 6 up through the pipe 42 into the stream passing through the pipe 18.

As hereinabove pointed out, the inner wall of the chamber 6 is so heated that the 100 upper part 66 is heated to a much lower degree of temperature than the wall of the part 56, and the unvaporized fuel striking the wall 66 and passing over it in a relatively thin film is acted upon by the heat 105 of said wall to cause only the more volatile portions of the fuel to be vaporized. The less volatile portions continue moving down the inner wall of the chamber 6 under the action of gravity striking parts of the wall 110 that are heated to higher temperatures, thus producing a fractional distillation of the fuel until the least volatile constituents of the fuel come into the hottest part 56 of the chamber 6 where they are eventually 115 120 vaporized.

It will be obvious that at times the mixture that is carried up through the pipe 42 will consist for the most part of vaporized fuel and that at other times some of the air 125 and more volatile vapors will be carried down into the lower part of the chamber 6 and drawn up through the pipe 42. In either case the heat content of the eventual mixture in the discharge pipe 18 will be 130

properly proportioned to the character of the mixture. This will be apparent from the fact that when the mixture drawn through the pipe 42 is made up largely of the vaporized heavier and less volatile portions of the fuel, the heat content of this mixture will be much greater than that of the air and more volatile portions that may be drawn through at other times and therefore the heat content 10 of the eventual mixture will be such as is required to maintain the heavier vapors in vaporized condition. The operation of the apparatus will therefore be substantially self-compensating.

15 This application, which formerly contained broad claims to the subject matter common to my co-pending applications herein above identified, has now been restricted to the novel subject matter herein disclosed.

20 which is not shown in said co-pending applications and broad claims to the subject matter common to all of said co-pending applications and particularly claims to the broad idea of differentially heating a vaporizing 25 surface and causing the liquid fuel to be vaporized to be directed on to this surface and to pass over it in the direction of increasing heat, have been made in my co-pending application Ser. No. 233,233, filed 30 May 9, 1918.

What I claim as new is:

1. A liquid fuel vaporizing device comprising, in combination, a vaporizing chamber having a heated wall surface over which the liquid fuel gravitates, means for directly heating the wall of the lower part of said chamber, the wall of the upper part of said chamber being heated only by conduction along the wall, a discharge pipe connected with the upper end of said chamber to receive the fuel vapor as formed and adapted to be connected with the intake of an internal combustion motor, a venturi or restricted passage in said discharge pipe, and a second pipe having one end opening into said chamber near its lower end and having its other end extended into said venturi or restricted passage to carry the heavier vapors from the lower end of said chamber into said 50 discharge pipe.

2. A liquid fuel vaporizing device comprising a centrifugal separating chamber for separating the unvolatilized portions of an atomized and partly volatilized fuel from the volatilized portions, a vaporizing chamber located below said centrifugal chamber and having a heated wall over which the unvolatilized portions of the fuel gravitate, means for effecting a differential heating of 55 said wall, comprising means for directly heating the wall at the lower end of said chamber, the wall at the upper end of said chamber being heated by conduction only along said wall, a discharge pipe adapted to 60 be connected to the intake of an internal

combustion motor and having its receiving opening in said vaporizing chamber, whereby all vapors and gases must pass into said chamber before entering said discharge pipe, a venturi in said discharge pipe and a second pipe having one end extended into the lower end of said vaporizing chamber and its other end in said venturi for lifting the heavier gases from the lower end of said vaporizing chamber.

3. A liquid fuel vaporizing device comprising, in combination, a vaporizing chamber having a differentially heated wall surface over which the liquid fuel gravitates, means for heating said surface arranged to cause the lower end of the wall surface to be heated to a much higher temperature than the upper end, a discharge pipe connected with said chamber near its upper end, a second discharge pipe opening into said chamber near its lower end and means whereby the movement of gases through said first mentioned discharge pipe effects a movement of the vaporized fuel from the lower end of said chamber through said second mentioned discharge pipe.

4. A liquid fuel vaporizing device adapted to be located between the intake of an internal combustion motor and an ordinary carburetor, said device comprising a centrifugal separating chamber for the atomized and partly volatilized liquid fuel from the carburetor arranged to separate the unvolatilized portions of said fuel from the volatilized portions, a vaporizing chamber below said centrifugal chamber having a differentially heated wall over which the unvolatilized portions of said fuel gravitate, means for heating said wall arranged to heat the lower end of said wall to a much higher temperature than the upper end, a discharge pipe adapted to be connected to the intake of the motor, opening into said vaporizing chamber near its upper end and having therein a restricted passage, a second discharge pipe extending into the restricted passage in said first mentioned discharge pipe and opening into said chamber near its lower end.

5. A liquid fuel vaporizing device adapted to be located between the intake of an internal combustion motor and an ordinary carburetor, said device comprising, in combination, means for separating the unvolatilized portion of the atomized and partly volatilized fuel received from said carburetor from the volatilized portions, a discharge pipe adapted to be connected to the motor intake and arranged to receive the volatilized fuel, a vaporizing chamber having a heated wall surface over which the unvolatilized portions of the fuel are adapted to gravitate, means for heating the wall of said chamber arranged to cause the lower end of the wall to be heated to a much higher degree of temperature than the upper end, and

- means extending into the lower end of said chamber and connected with said discharge pipe for lifting the heavier portion of the vaporized fuel from the lower end of said chamber and carrying them into the current of fuel passing through said discharge pipe.
6. A liquid fuel vaporizing device comprising, in combination, a vaporizing chamber having a heated wall surface over which the unvolatilized fuel gravitates, means for heating said wall surface arranged to heat the surface at the lower end of said chamber directly by conduction through the wall and to heat the surface at the upper end of said chamber only by conduction along the wall whereby degrees of vaporizing heat appropriate to the volatility of the different fuel constituents are supplied as said fuel gravitates from the upper to the lower end of said wall surface, a discharge pipe adapted to be connected to the intake of an internal combustion motor, opening into the upper end of said chamber and adapted to receive the more volatile portions of the fuel as they are vaporized, a second discharge pipe extending into the lower end of said chamber to receive the heavier portions of the vaporized fuel as they are vaporized in the lower part of said chamber, and means for creating a lifting differential of pressure in said second mentioned discharge pipe arranged to carry the less volatile portions of the fuel when volatilized into the stream to the motor intake.
7. In a device of the class described, adapted to be located between the intake of an internal combustion motor and an ordinary carburetor, a centrifugal separating chamber for separating the unvolatilized portions of an atomized and partly volatilized fuel from the volatilized portions, a vaporizing chamber below said separating chamber and with which said separating chamber communicates, said vaporizing chamber having a heated wall over which the unvolatilized portions of the fuel gravitate, means for heating said wall arranged to cause the lower end of the wall to be heated to a much higher temperature than the upper end, a discharge pipe for the air and vaporized fuel communicating with said vaporizing chamber near its upper end and into which the air and vaporized fuel is free to pass, a second discharge pipe com-
- municating with said vaporizing chamber near its lower end, and means whereby the passage of the air and vaporized fuel through the first mentioned discharge pipe creates a pressure differential for moving the heavier vaporized fuel from the lower end of said vaporizing chamber through said second-mentioned discharge pipe.
8. A liquid fuel vaporizing device comprising, in combination, a vaporizing chamber having a differentially heated wall surface over which the liquid fuel to be vaporized gravitates, means for heating said surface arranged to cause the lower end of said surface to be heated to a much higher temperature than the upper end, a discharge pipe for said vaporized fuel communicating with said chamber near its upper end, a second discharge pipe communicating with said chamber near its lower end and also communicating with said first mentioned discharge pipe, and means whereby the movement of the vaporized fuel through said first mentioned discharge pipe creates a pressure differential in said second discharge pipe for carrying the heavier fuel vapor from the lower end of said chamber into the stream of vaporized fuel from the upper end of said chamber.
9. Fuel vaporizing means comprising, in combination, a cylindrical separating chamber having a tangential intake, a vaporizing chamber below said separating chamber and with which said separating chamber communicates through its bottom, a discharge pipe extending centrally through said separating chamber and opening into said vaporizing chamber, means for heating the wall of said vaporizing chamber arranged to cause the lower end of the wall surface to be heated to a much higher temperature than the upper end, a second discharge pipe located within said vaporizing chamber and extending to a point near the bottom thereof and having its other end located within said first mentioned discharge pipe, a venturi or restricted passage about the upper end of said second discharge pipe, said vaporizing chamber being also restricted in diameter about the lower end of said second discharge pipe.

Signed at Canton, Ohio, this 31st day of Dec. 1920.

WILLIAM H. HILL.
